PROCESS FOR DEWAXING OILS

Ulric B. Bray, Palos Verdes Estates, and Donald E. Carr, Naples, Calif., assignors to Union Oil Company of California, Los Angeles, Calif., a corporation of California

Application November 6, 1933, Serial No. 696,892

15 Claims. (Cl. 196—18)

The present invention relates to a process for separating asphalt and wax from oils in the production of lubricating oil. More particularly, it relates to a process for separating wax from wax containing oils in a plurality of stages.

Processes are now known for dewaxing oils for the production of lubricating oils wherein liquefied normally gaseous hydrocarbon solvents or diluents, such as liquid propane are employed. In such processes the wax containing oil is commingled with the diluent under a pressure sufficient to maintain the diluent in the liquid state at room temperatures. If the oil contained asphaltic impurities, these will precipitate in the presence of the diluent and settle to the bottom of the decanter after which the oil solvent solution containing the wax is decanted from the settled asphaltic impurities. The pressure on the solution is then gradually reduced to permit vaporization of the diluent which causes the remaining solution of oil and diluent to be chilled and thus precipitate the wax. Temperatures of approximately —40° F. may be obtained by the evaporation of the diluent under reduced pressure. The precipitated wax is separated in the presence of the remaining diluent by filtration, settling or centrifuging. If sufficient diluent is not present in the oil subsequent to refrigeration to give a good separation of the oil solvent solution from the precipitated wax, additional quantities of diluent are added.

However, in such processes involving the use of liquefied normally gaseous hydrocarbon diluents such as liquid propane, difficulty has been experienced in dewaxing the oils, particularly light refined oils containing high wax contents to low pour points. We have observed that wax containing oil contains two types of waxes, i. e. a heavy, hard wax of high melting point which precipitates and settles readily from the solution of oil and diluent and a second soft, light wax of low melting point which does not precipitate nor settle as readily. The waxes of low melting point present in oils have a solubility in such solvents or diluents as propane at dewaxing temperatures of approximately —40° F. or lower which is considerable. When substantial amounts of propane diluent are employed, this may result in the solution of sufficient wax to amount to a difference in pour point of 20 to 30° F. between the depropanized dewaxate, i. e. the dewaxed oil, and the same dewaxate when rendered free of light wax impurities.

If such oils are dewaxed in the presence of low volumetric ratios of propane to oil, serious

difficulties arise in attempting to filter efficiently. The filter rates on the basis of the viscous oil are very low and the back pressures across the filter cake are high and furthermore the filter cake must be repeatedly washed to bring the recovery of oil up to the theoretical yield. With some oils the concentration of wax is very high and the aforementioned difficulties are more pronounced when attempting to dewax such oils. This is particularly true in dewaxing oils which have previously been heavily treated with extractive solvents, such as liquid sulphur dioxide employed to remove the aromatic components in the oil. As a consequence of this removal of oil fractions, the wax which is sparingly soluble in the fractions removed or the extract phase of the extraction is concentrated in the raffinate phase or the desirable lubricating oil fractions.

On the other hand, if a sufficiently high propane oil ratio is used to give economical filter rates and good yields, the pour points of the oils are raised 10 to 30° F. due to the solubility of the wax in the propane.

It is, therefore, an object of our invention to improve upon the aforesaid process for dewaxing oil employing liquefied normally gaseous hydrocarbon solvents such as liquid propane.

A particular object of our invention resides in removing substantially all of the wax in the oil in the presence of a liquefied normally gaseous hydrocarbon solvent and to produce lubricating oils of low pour points.

It is another object of our invention to provide a process which will facilitate removal of wax from oils without serious disadvantage in filters.

We have discovered that the solubility of wax in the coexistent lubricating oil itself is much lower than in such liquefied normally gaseous hydrocarbon diluents as liquid propane or similar dewaxing solvents. In fact this phenomenon is what makes the older method of cold pressing oils at the relatively high temperatures of approximately 10 to 20° F. practicable. Cold pressing of undiluted oils would be a very effective method of wax separation were it not for the severe limits placed on the process by the viscosity of the oil. This is also the case in dewaxing oils with a low ratio of diluent, particularly in the case of oils of high viscosity or of high wax content.

As a consequence of the above discovery, we propose to separate the wax from oils in a plurality of stages employing a higher propane ratio in the first stage than in the subsequent stage or stages. We find that in the first dewaxing stage,

the major portion of the wax, particularly the higher melting point, hard wax is removed and this can be effected in the presence of a high propane to oil ratio of approximately 5 volumes 5 of propane to one volume of the oil. This dilution of the oil is sufficient to give satisfactory filter or settling rates. However, the filtrate will have a high pour point as, for example, 15 or 20° F.

10 With the removal of the major portion of the wax contained in the oil, the wax concentration in the remaining oil will be lowered sufficiently as to permit employment of lower propane to oil ratios in the subsequent removal of the remaining 15 wax in the oil. The reduction of the propane to oil ratio causes relatively higher lubricating oil to propane ratio so that the remaining wax in the oil will readily precipitate from the solution. Thus, the oil solvent solution from which a major 20 proportion of the wax has been removed and comprising approximately five volumes of propane to one of oil may be further chilled by evaporating solvent under reduced pressure until only a sufficient amount remains to dilute the 25 oil and reduce its viscosity. The propane ratio should be reduced until approximately one or one and one-half volumes of propane to one of the oil remains in solution. The oil solvent solution is then digested with the changed conditions 30 of solvent oil ratio and/or temperature until complete equilibrium has been obtained. The digestion of the solution effects wax crystal growth. The solution may then be filtered to remove additional soft wax which has been precipitated by the reduction of propane to oil ratio 35 and/or by further chilling. If desired, further dewaxing of the filtrate may be accomplished at progressively decreasing propane to oil ratios either at the same temperature or at lower temperatures in subsequent stages. Generally, however, two stages will suffice to produce a lubricating 40 oil when freed of solvent of low pour point.

The adjustment of temperatures and solvent ratios to give a proper balance between the first 45 and second filtrations or separations depends, of course, on the solvent employed and the nature of the stock treated.

It will be observed that in the present discussion of our invention, we intend to include as 50 diluents or solvents also such hydrocarbon fractions as are normally vaporous at ordinary temperature and pressure. Such hydrocarbons include methane, ethane, propane, butane, isobutane and mixtures thereof. These volatile solvents 55 may be obtained by rectification of casinghead gasoline by the so-called "stabilization" method now conventional in the natural gasoline industry. They may be obtained as the overhead in the stabilization or may be obtained as a side 60 stream product from plates near the top of the stabilizing column. When obtained as overhead vapors, they are liquefied by compression and cooled in the conventional manner and are drawn off into pressure chambers where they are maintained in a liquid state until used. A typical 65 analysis of such an overhead fraction is 6.7% ethane, 72.2% propane, 19.9% isobutane and 1.2% normal butane, whereas a side stream product may consist of as high as 98% propane. Such a 70 fraction may be maintained in a liquid state at a pressure of approximately 125 lbs. per square inch at a temperature of about 75° F. The predominating hydrocarbon member in this mixture is propane and hereafter when we use the term "propane" or "liquid propane" we are

referring to such a fraction. We also intend to include the use of other dewaxing solvents which are liquid at ordinary temperatures and pressures. Such solvents include naphtha, mixtures of benzene and acetone, dichlorethylene, trichloroethylene, methylene chloride, etc.

Stated briefly, therefore, our invention comprises a process for separating wax in the production of lubricating oils from oils containing wax which comprises separating the wax by refrigeration in the presence of a diluent in a plurality of stages and in which the solvent to oil ratio is decreased as wax is separated from the oil in the prior stages of operation. The invention has, as one of its features, the use of liquefied normally gaseous hydrocarbon solvents, as liquid propane, as diluents for refrigeration of the oil to precipitate wax and to give good settling and filtration of the solution containing precipitated wax. The invention also includes the employment of progressively decreasing temperatures for wax precipitation in the several stages of the process.

More specifically this invention comprises a process for dewaxing lubricating oil stocks where- 25 in the oil is dissolved in a liquefied normally gaseous hydrocarbon solvent, as liquid propane, under pressure sufficient to maintain the solvent in a liquid state, in then reducing the pressure of the oil propane solution containing wax to 30 vaporize a portion of the propane and thus chill the oil to precipitate the wax, in then removing the precipitated wax from the oil propane solution, in subsequently removing a portion of the remaining propane from the oil propane solution 35 and digesting the remaining oil propane solution to effect further precipitation of wax at a lower propane to oil ratio than that accompanying the separation of wax in the first stage, in separating the precipitated wax from the oil propane solution and in finally separating the propane from the oil. As a specific example of the process, we may employ a volumetric propane to oil ratio of 40 5 to 1 in the first stage of the process to separate the major portion of the wax from the oil and subsequently separating the remaining wax at the lower propane to oil ratio of 1 or 1½ to 1. The wax precipitation and separation in the first 45 stage may be effected at a temperature of 0° F. and that in the second stage may be accomplished at a temperature of -40° F., or the separation in both stages may be accomplished at the same temperature of approximately -40° F. If desired, the process may be carried out in three 50 stages of wax separation. In the first stage, the wax may be separated at 0° F. in the presence of 5 volumes of propane to one volume of the oil, in the second stage at a temperature of -40° F. in the presence of 3 volumes of propane and in the third stage at a temperature of -55° F. in the 55 presence of one volume of propane to one of the oil; or the three stages employing volumetric ratios of 5, 3 and 1 volumes of propane, respectively, to one of the oil, may be carried out at the same temperature of say -45° F. The important 60 feature of this invention resides in the use of decreasing volumetric ratios of propane to oil as wax is separated from the solution of oil and propane so as to permit wax which is dissolved in the propane at the higher volumetric ratios to precipitate from solution when reducing the volumetric ratio in the later stages.

Other objects and advantages of our invention will be apparent from the following description of our invention taken from the drawing which 75

refers to a schematic arrangement of apparatus for carrying out the invention:

Referring to the drawing, an asphalt and wax containing oil is taken from tank 1 and is drawn into line 2 controlled by valve 3 by pump 4 where it meets a liquefied normally gaseous hydrocarbon solvent such as liquid propane taken from storage tank 5 via line 6 and pump 7 which forces the liquid propane through valve 8 into line 2. The amount of propane introduced into line 2 will depend upon the character of the oil but should be sufficient to precipitate substantially all of the asphalt present in the oil. This amount may vary from 3 to 8 volumes of propane and upwards to one volume of the oil. If desired, the amount of propane mixed with the oil may be regulated so as to give the proper degree of chilling by evaporation of propane under reduced pressure in the subsequent wax precipitating stages as will be described hereinafter. The mixture of liquid propane and oil containing asphalt and wax is passed through turbulence or mixing coil 9 into decanter or asphalt precipitator 10 where the asphalt in the oil is precipitated and settles rapidly as a slurry of substantially pure bitumen or hard asphalt containing some oil and propane. A pressure of approximately 125-175 lbs. per square inch and a temperature of about 70° F. to 80° F. is maintained in the decanter 10. Pressures within the above range will be sufficient to maintain the propane in a liquid state at such temperatures. The pressure in decanter 10 may be maintained by means of equilibrium line 11 controlled by valve 12 which connects the decanter 10 with the high pressure storage tank 5.

The asphalt precipitated from the oil in decanter 10 may be withdrawn via line 14 controlled by valve 15 as a slurry of substantially pure bitumen containing some oil and propane. This mixture may be treated for removal of propane and reduction of the remaining asphalt to proper specification such as flash and fire points. This will be readily understood by those skilled in the art. The propane contained in the slurry which may be removed by distillation may be recovered by compression and cooling and returned to propane storage tank 5.

Instead of precipitating and separating the asphalt from the oil in one decanter as described above, the asphalt separation may be carried out countercurrently in several stages. For example, the oil from tank 1 may be mixed with a propane oil solution of a second stage to precipitate a liquid asphalt, that is, an asphalt containing a substantial amount of oil and this asphalt may then be mixed with fresh propane and passed into the second stage where the oil remaining in the asphalt is dissolved with fresh propane and decanted from the remaining substantially pure bitumen. This solution is then employed to treat the oil from tank 1 as aforesaid. Likewise, the solution of oil and propane from the first stage may be mixed with further quantities of fresh propane to precipitate additional asphalt from solution.

The overflow from decanter 10 consisting of propane and oil substantially free from the asphaltic materials separated in decanter 10 but containing wax and other wax-like impurities, is sent through line 16 and pressure reduction valve 17 into the first chilling column 18 where sufficient propane vaporizes to reduce the temperature of the remaining material to a low temperature sufficient to precipitate a substantial portion of the wax contained in the oil. The

temperature in chiller 18 is reduced to approximately 0° F. or lower and preferably at a gradual rate, i. e. not in excess of 3 or 4° F. per minute. This may be accomplished by controlling the pressure in chiller 18 by the proper operation of valve 20 on line 19 and compressor 22 which is connected to the chiller by lines 19 and 21. The pressure will be gradually lowered in column 18 to about 25 lbs. gauge which corresponds to a temperature of approximately 0° F. If desired, the temperature may be rapidly lowered at a rate of about 10° F. per minute until a temperature of approximately 30 to 40° F. is attained which corresponds to the cloud point or the point where wax begins to precipitate from solution. The mixture may thereafter be gradually lowered to 0° F. at a rate of approximately 3° F. per minute. The propane evaporating in column 18 is withdrawn via line 19 controlled by valve 20 and passes via line 21 to the suction of compressor 22 where the vapors are compressed, pass through line 23, liquefied in cooler 24 and run down to propane storage tank 5.

Due to the fact that sufficient time must be given to gradually chill the solution of oil and propane in column 18 and to make the process continuous, a plurality of chilling columns 18 may be provided and operated alternately. However, when operating a batch process, merely one of such chilling columns will be sufficient. Thus, the entire charge from decanter 10 may be transferred into the column 18 and the chilling accomplished by controlling the operation of valve 20 on line 19. If the solution of oil and propane entering the chiller 18 does not contain sufficient propane to effect the desired chilling, further quantities of liquid propane may be mixed with the solution entering the chiller to give the desired refrigeration of the oil.

In the preferred operation when using propane as a solvent, it is desirable to maintain a volumetric ratio of approximately 5 volumes of propane to one volume of oil, that is, the oil and propane is initially introduced into the chiller as a mixture of 5 volumes of propane to one volume of oil and as the propane is vaporized further quantities of liquid propane are introduced to make up for that vaporized and to maintain the volumetric ratio of 5 to 1. When the temperature in the chiller has been reduced to approximately 0° F., the mixture of propane and oil containing precipitated wax is withdrawn from the bottom of the chiller via line 25 controlled by valve 26 and pumped by pump 27 into the vapor tight wax separator or settler 28. In batch operation, merely one of such settlers will suffice but to make the process continuous a plurality of these settlers may be employed and operated alternately and thus provide for sufficient settling periods. In order to prevent ebullition in the wax settler during the wax settling operation, pressure is imposed upon the solution of oil. This is accomplished by maintaining pressure within the separator by pump 27. As the chilled mass in the wax separator remains in a non-ebullient state, the wax settles out and is collected by vanes 29 operated by pulley 30 connected to a suitable source of power not shown. Instead of employing settling for separating the precipitated wax, the separation may be accomplished by filtration or centrifuging.

The wax slurry collecting at the bottom of the wax settler is withdrawn via line 31 controlled by valve 32 and treated for removal of residual

propane and oil from the wax such as by heating the slurry to temperatures sufficient to vaporize the propane and oil. The propane may be compressed and cooled and returned to propane storage tank 5. The oil is preferably removed from the wax slurry by washing with fresh propane.

The propane solution of oil containing unprecipitated wax is withdrawn from the separator 28 and passed into line 33 controlled by valve 34 and pumped by pump 35 through line 36 into a second chilling column 37 where the solution is chilled to a temperature of approximately -40° F. by vaporization of propane in a manner similar to that described in chiller 18. It is preferable to vaporize the propane in chiller 37 at a rate not greater than 3° F. per minute. The vaporization of propane in chiller 37 is controlled by gradually lowering the pressure by means of valve 39 on line 38 to approximately 0 lbs. gauge which corresponds to a temperature of -40° F. The vaporized propane from chiller 37 passes via line 38 and valve 39 into line 21 to compressor 22, cooler 24 and propane storage tank 5. The vaporization of propane in chiller 37 is continued until approximately one and one-half volumes of propane to one volume of oil remain in the chiller. This amount of propane is sufficient to dilute the oil and reduce its viscosity so that the precipitated wax may be readily separated by filtration. The chilled mixture is digested for a period of time under the changed conditions of solvent ratio and temperature until complete equilibrium has been attained. The reduction of solvent ratio permits a substantial amount of soft wax which is soluble in propane to precipitate from solution.

The precipitated wax, oil and propane is withdrawn from the chiller 37 via line 49 controlled by valve 41 and pumped by pump 42 through line 43 through filter 44 where the precipitated wax is separated from the propane oil solution. The separated wax is withdrawn from the filter via line 45 controlled by valve 46 and passed to suitable heating and propane separating apparatus where the vaporized propane may be compressed, cooled and returned to propane storage tank 5. The wax free solution of propane and oil is passed through line 47 controlled by valve 48 and pumped by pump 49 through line 50 into heater 51 which is provided with mist extractor 52 where the propane present in the oil is vaporized by the aid of steam circulated through the closed steam coil 53. The vaporized propane passes out of the heater through line 54 controlled by valve 55, cooled in cooler 56 and then passes through lines 57, 38 and 21 to compressor 22, cooler 24, into propane storage tank 5. The dewaxed propane free oil passes from heater 51 by means of line 58 controlled by valve 59 to pump 60 which passes the oil into storage tank 61.

The dewaxed oil may be chemically treated, as, for example, by means of sulphuric acid to remove unsaturated oil and other impurities from the oil which is subsequently water washed and neutralized with alkali, such as sodium hydroxide and/or clay. The chemical treatment may be performed in the presence of a diluent, such as the propane employed in the dewaxing steps and this operation may be carried out either subsequent to the final wax separation stage or at any of the intermediate dewaxing stages while the solution is in a chilled condition or prior to the wax separation stages, as, for example, subsequent to the removal of asphalt.

The foregoing is a description of a process as carried out on residual oils or lubricating oil stocks containing both asphalt and wax. Where oils to be treated are substantially free from asphalt, the asphalt precipitating and separating stage is omitted and the solution of propane and oil is directly treated for wax removal by introducing the mixture of waxy oil and propane into chilling column 18.

The following is a description of the invention as carried out on one type of oil employing liquid propane as a diluent and internal refrigerant:

An S. A. E. 10 Santa Fe Springs raffinate, produced by extracting a wax containing oil with a mixture of 70% liquid sulphur dioxide and 30% benzene, and containing approximately 30% by weight of wax was mixed with approximately 9 volumes of propane and passed into decanter 18. A temperature of approximately 75° F. and a pressure of about 150 lbs. per square inch was maintained in decanter 18. In chilling column 18, sufficient propane was vaporized to reduce the temperature of the mixture to approximately -19° F. to precipitate a substantial portion of the wax. The mixture of precipitated wax, oil and propane was permitted to digest under pressure for approximately twenty minutes and settle, approximately 5 volumes of propane to one volume of the oil being maintained during the wax settling period in settler 28. The settled precipitated wax was withdrawn and then washed with further quantities of propane to remove any oil present in the wax. The quantity of wax recovered comprised approximately 25% by weight of the charge and had a melting point of approximately 130° F. Ubbelohde. The oil in approximately 500 volume percent of propane having a pour point of approximately 20° F. was then chilled to approximately -42° F. by vaporization of propane. Approximately one volume of propane remained in the oil. This chilling caused the remaining wax to precipitate from solution. The mixture of propane, oil and precipitated wax was then digested under pressure for about fifteen minutes and was then passed through a filter where the precipitated wax was separated from the oil propane solution. This wax was also washed with further quantities of propane to remove any contained oil in the wax. The melting point of this wax approximated 105° F. Ubbelohde. The filtrate was then de-propanized by evaporation. The wax free oil showed a pour point of approximately -15° F.

As a modification of the above, the wax separation process may be accomplished in three stages of chilling and wax separation, for example, the first wax may be precipitated at a temperature of 0° F. and filtered in the presence of approximately 500 volume percent of propane. The propane oil solution may then be chilled to approximately -40° F. and filtered in the presence of approximately 300 volume percent propane, after which the propane oil solution may be chilled to -55° F. by maintaining a vacuum in the chiller and filtered in the presence of 100 volume percent of propane. If desired, the wax separation or filtration in the three stages may be accomplished at the same temperature of approximately -45° F., employing, however, 500, 300 and 100 volume percent of propane, respectively, during the filtration stages.

In some instances, we find it advantageous to precoat the plates of the filter with such filter aids as diatomaceous earth, fuller's earth, clay, 75

wood flour or sawdust, prior to filtration. By depositing a thin layer of any of the foregoing materials upon the filter plates prior to passing the chilled mixture of propane and oil containing precipitated wax through the filter, we are sometimes able to obtain a more thorough separation of the precipitated wax from the oil dissolved in propane. In carrying out this type of operation, we first mix a small quantity of the precoating materials, such as diatomaceous earth, etc., with liquid propane and pass this mixture through the filter. The precoating substance suspended in the liquid propane deposits itself in a thin layer over the filter plate and the propane is withdrawn from the filter press as a clear filtrate. The chilled oil dissolved in liquid propane carrying precipitated wax in suspension is now forced through the filter press and the precoating materials present on the filter plates aid in separating the wax from the propane solution of oil. While we may employ any of the foregoing materials as precoating substances for the filter press, we have found wood flour to be especially well adapted for this purpose. If desired, the filter aids may be admixed with the propane solution of oil either prior to chilling or subsequent thereto and prior to passage of the chilled mixture through the filter press.

The use of wax crystallization inhibitors or modifiers, such as condensation products of aromatics with paraffinic hydrocarbons produced by a Friedel-Craft reaction between chlorinated paraffin wax and an aromatic hydrocarbon, is sometimes helpful in producing a wax precipitate which is more easily filtered from the solvent solution of oil. The wax crystallization inhibitor functions in such manner as to promote crystal growth in the present instance. The crystallization inhibitor may be added to the waxy oil or to the solution of the waxy oil in the solvent at any stage during the chilling operation but for the best results, it is usually preferable to add the crystallization modifier before the chilling or concentration of the solvent is begun in preparation for a given filtration operation. For instance, the crystallization modifier may be added to the original mixture of oil and propane at atmospheric temperature or it may be added after the first stage of wax separation before further concentration of solvent is effected as explained above.

In place of the above condensation products, we may use other asphaltic, pseudo-asphaltic or colloidal bodies, such as heavy residual oils, asphalt, cracked residues or high molecular weight fractions obtained from these by distillation or solvent extraction. We may also add as wax crystallization inhibitors high molecular weight wax bodies and oxidized acidic bodies, metal soaps of organic acids and the like.

It is to be understood that the above description is merely illustrative of preferred embodiments of our invention of which many variations may be made by those skilled in the art without departing from the spirit thereof.

We claim:

1. A process for separating wax from oils containing the same which comprises mixing said oil with a hydrocarbon solvent which at elevated temperatures completely dissolves both oil and wax and which at dewaxing temperatures completely dissolves oil but only dissolves small but appreciable amounts of wax, chilling the oil solvent solution to precipitate wax, separating the precipitated wax from the oil solvent solution in

a plurality of stages and at decreasing solvent to oil ratios.

2. A process as in claim 1 in which the solvent comprises a liquefied normally gaseous hydrocarbon. 5

3. A process as in claim 1 in which the solvent comprises liquid propane.

4. A process for separating wax from oils containing the same which comprises mixing said oil with a hydrocarbon solvent which at elevated 10 temperatures completely dissolves both oil and wax and which at dewaxing temperatures completely dissolves oil but only dissolves small but appreciable amounts of wax, chilling the oil solvent solution to precipitate wax, separating the 15 precipitated wax from the oil solvent solution, separating a portion of the solvent from the oil solvent solution to effect further precipitation of wax, separating the last mentioned precipitated wax from the oil and remaining solvent 20 and separating the remaining solvent from the oil.

5. A process for separating wax from oils containing the same which comprises mixing the oil with a liquefied normally gaseous hydrocarbon 25 solvent under pressure, reducing the pressure on the oil solvent solution to vaporize a portion of the solvent to chill the oil and precipitate wax, separating the precipitated wax from the oil solvent solution, separating further quantities of 30 solvent from the oil solvent solution to permit further quantities of wax to precipitate from solution, separating said last mentioned precipitated wax from the oil in the presence of the reduced quantity of solvent and separating the remaining solvent from the oil. 35

6. A process for separating wax from oils containing the same which comprises mixing said oil with liquid propane under pressure sufficient to maintain said propane liquid, reducing the pressure and vaporizing a portion of the propane to chill the oil and precipitate wax, separating the precipitated wax from the oil propane solution, vaporizing further quantities of propane from the oil propane solution to reduce the concentration 40 of propane in the oil propane solution and thus precipitate further quantities of wax, separating said last mentioned precipitated wax from the oil and propane and separating the propane from the oil. 45

7. A process for separating wax from oil containing the same which comprises mixing said oil with a hydrocarbon solvent which at elevated 55 temperatures completely dissolves both oil and wax and which at dewaxing temperatures completely dissolves oil but only dissolves small but appreciable amounts of wax, chilling the oil solvent solution to a wax precipitating temperature to precipitate a substantial portion of the wax, separating said precipitated wax from the oil and solvent, lowering the concentration of solvent in the oil to permit further quantities of wax to precipitate from solution and reducing the temperature to a still lower wax precipitating 60 temperature to precipitate further quantities of wax, separating said precipitated wax from the oil in the presence of said lower concentration of solvent and separating the said solvent from the oil. 65

8. A process as in claim 7 in which the solvent comprises a liquefied normally gaseous hydrocarbon. 70

9. A process as in claim 7 in which the solvent comprises liquid propane.

10. A process for separating wax from oil con- 75

taining the same which comprises mixing said oil with liquid propane under pressure, reducing the pressure of the oil propane solution to vaporize a portion of the propane to chill the oil and thus 5 precipitate the wax, separating said precipitated wax from the oil and remaining propane, reducing the pressure further to vaporize further quantities of propane and thus chill the oil to a lower temperature than said first chilling operation to 10 precipitate further quantities of wax, separating the precipitated wax in the presence of a lower concentration of propane and separating the propane from the oil.

11. A process for separating wax from oil containing the same which comprises mixing said oil with a liquefied normally gaseous hydrocarbon under superatmospheric pressure, vaporizing a portion of the solvent under reduced pressure to chill the oil and precipitate a portion of the wax 15 and to leave a volumetric ratio of solvent to oil in excess of 1 to 1½, removing the precipitated wax from the oil and solvent, vaporizing a further portion of the solvent to chill the oil to a lower temperature to precipitate a further portion of wax and removing the precipitated wax 20

25

in the presence of approximately 1 to 1½ volumes of solvent to one of the oil and subsequently separating the solvent from the oil.

12. A process as in claim 7 in which the solvent is substantially liquid propane. 5

13. The process of removing wax from lubricating oils comprising dissolving the oil and wax in a liquefied normally gaseous diluent, cooling the solution to cause a major portion but less than all of the wax to precipitate, separating the precipitated wax, removing a portion but less than all of the diluent from the partially dewaxed oil solution and simultaneously chilling said oil solution to a lower temperature to cause precipitation of the remaining wax, separating the wax 10 precipitated at said lower temperature from the oil solution, and removing diluent from said last mentioned oil solution. 15

14. A process as in claim 13 in which the diluent comprises a liquefied normally gaseous hydrocarbon. 20

15. A process as in claim 13 in which the diluent comprises liquid propane.
